UNITED STATES PATENT OFFICE.

WALTER HANEY, OF FORNEY, TEXAS.

AUTOMATIC PRESS STOP.

Application filed October 4, 1926. Serial No. 139,432.

This invention relates to automatic devices for presses, and has more particular reference to a means for cutting off the power by which the press is operated in the event 5 the head block of the press becomes canted within the press cylinder.

In the pressing of lint cotton into marketable bales, the lint is placed in the press through the top of the cylinder with a 10 denser from the gin stands and then pressed within the baler cylinder. The next step is usually to press the bale to about four times its original density, and this by moving upwardly of the lower head block. In 15 the process of baling lint it frequently happens that said lower head block becomes canted within the cylinder causing an irregular bale or the ends of the head block to be pushed out and broken.

20 The primary object of the invention is to automatically cut off the power, be it steam, electric, or otherwise, should said head block become canted at the end of its movement within the cylinder; and to make all bales 25 of lint cotton of a uniform size.

Other objects and advantages of the invention will become apparent as the nature of the invention is better understood, the same comprising the novel form, combination, 30 and arrangement of parts hereinafter more fully described, shown in the accompanying drawing and claimed.

In the drawings wherein like reference characters indicate corresponding parts in 35 Figures 1 and 2, and in Figures 3 and 4, respectively, the diagrammatic view, Figure 5 being common to both forms of the invention:

Figure 1 is a view in vertical section of 40 a cotton press equipped with an automatic stop mechanism constructed in accordance with the present invention.

Figure 2 is an elevation of an electric switch mechanism operable in the event the 45 head block becomes canted within the cylinder, this form of the invention being employed when the press is operated electrically.

Figure 3 is a view similar to Figure 2 of 50 a belt shifting mechanism operable only in the event the head block becomes canted within the cylinder at the end of its compression stroke for cutting off the power to the operating mechanism, this form of the 55 invention being provided when the pressing

units are controlled by belt driven power.

Figure 4 is a view similar to Figure 2, but disclosing the second form of the invention, and

Figure 5 is a diagrammatic view of the 60 structural elements of the invention common to both forms of the device disclosed in the drawing.

First having reference to Figures 1 and 2, 5 designates a cotton press cylinder within 65 which are operable plungers 6 and 7, frequently termed "head blocks", the upper one of which is movable out of the upper open end of the cylinder so as to permit the cotton to be fed therein. In the usual operation of such a baler, the cotton is first disposed into the cylinder when the lower head block 7 is at the bottom of the cylinder as indicated in full lines in Figure 1. The cotton is then pressed initially by the plunger 75 6. The bale is then pressed to about four times the original density by forcing upwardly upon the lower plunger or head block 7 to the position as indicated by the dotted lines in Figure 1. As heretofore 80 mentioned, said lower plunger or head block frequently becomes canted at the end of its compression stroke within the cylinder, as indicated by the dotted lines in Figure 1 85 causing an irregular bale, and frequently damage to the head block and cylinder.

In order to overcome this undesirable feature, I attach to the bottom side of the head block 7 at opposite sides of the plunger rod 7' certain ends of rope or cable lengths 8-8. 90 These cable lengths are trained over pulleys 9-9 disposed within the lower end of the cylinder and are then directed outwardly in spaced parallel relation through an opening 10 in the bottom of the cylinder. As clearly 95 illustrated in the diagrammatic view in Figure 5, the rope or cable lengths 8-8 are then directed beneath other laterally spaced pulleys 11-11 and thence directed upwardly and in turn trained over other laterally spaced pulleys 12-12 in vertical alignment with the pulleys 11-11. The cable lengths are then directed horizontally in spaced parallel relation, and are trained over still further pulleys 13-13 in spaced horizontal relation with the pulleys 12-12. The pulleys 11, 12, and 13 are preferably arranged upon a supporting panel or suitable supporting wall within the gin house directly adjacent the press as indicated in Figure 1, said panel 100 105 110

or supporting wall being designated by the reference character A. The cable lengths are thence directed to an opening 14 in the panel or supporting wall A, the same being trained over pulleys 15—15, preferably disposed upon a common shaft that traverses the opening, as more clearly brought out in Figure 2. Beneath this opening 14 there is provided a pair of longitudinally spaced pulleys 16, over which the rope or cable lengths are trained, the same thence passing laterally in close relationship and attached to the end of the elongated arm 17 of a bell crank 18 that is pivoted at 19 to the adjacent side of the panel or supporting wall A.

Counterweights 20—20 are hung upon the rope or cable lengths 8—8 intermediate the spaced pulleys 12 and 13. The length of the cables or ropes is such that the plunger or head block 7 may be raised and lowered within the cylinder 5 to the limit of movement in opposite directions as indicated by the full and dotted lines in said Figure 1, the slack being taken up when the plunger or head block is at any intermediate position other than its full uppermost position by the counterweights 20—20 with the end in view that the bell crank 18 will not be swung upon its pivot 19 during such a movement of the plunger or head block when its upper limit of movement is in true horizontal position within the cylinder. As a result, the plunger in the normal reciprocating movement between the full and dotted line positions shown in Figure 1 will not affect or operate the levers 17 or 33 of Figures 2 and 3 respectively for stopping the press, so long as the plunger at the end of its upper limit of movement is not canted. It is immaterial whether the head 7 of the plunger cant during the intermediate portion of the stroke as the controlling action is not desired at this point but only at the time it completes its stroke of movement in advance of the operation of the tying mechanism for tying up the compressed bale.

In the operation of presses for baling cotton, it frequently happens that the cotton is not evenly distributed in the compression chamber and as a result the plunger will become canted, due to the unequal compression in opposite sides of the chamber. If the operator of the press observes this condition before the plunger reaches the upper end of its stroke of movement, he can usually push sufficient of the cotton over from one side to the other to properly distribute it in order to provide a uniform bale in the complete compressed relation. However, if the operator happens to leave the machine for a short interval of time, it is possible that this redistribution of cotton cannot be obtained and as a result, an irregular-shaped and large ended bale will be compressed, by the time the plunger reaches the end of its

stroke at which point it will be in a canted position. If, in this condition the large ended bale is tied out by the operator which he can frequently do in the further operation of the mechanism in completing the bale, it frequently happens that the canting of the plunger may cause a portion to pass the doors of the press and cause the same to break the crimp off the hydraulic plunger or to injure other adjacent parts of the press, preventing the further efficient operation thereof.

As the big ended bales cannot be used, it is therefore advantageous to prevent the same from being formed and tied out. As a result, this invention operates only at the time of forming a big ended bale to prevent tying out of the bale and stopping the operation of the press.

In obtaining the control of the press, this mechanism acts only at the upper limit of the stroke of movement of the plunger 7, so that should this plunger be canted at this upper limit of movement, and the end of the plunger will be moved beyond its normal limit of movement such as indicated by the portion of the plunger 7 at the left hand side of Figure 1 in the dotted line position at angular relation to the stem, which movement is taken advantage of in producing an abnormal movement of the cable 8, which operates the switch controlling lever or the belt controlling mechanism.

In this way, the entire baling press is stopped, so that the operator cannot tie out the bale by continuing the operation of the machine to produce an operation of the tying mechanism. As a result, large ended bales cannot be tied out and must be removed from the press and the operation again started to obtain the proper distribution of the cotton in the formation of the bale, so that the plunger 7 will not cant when it reaches its upper limit of movement.

While the illustration shown in the drawing provides cables 8 connected to the plunger 7 at a pair of points in diametrical opposite positions with respect to the mounting for the plunger, it is obvious that should the plunger cant in a plane at right angles to the plane of these connections, that control for this canting movement could be obtained by using additional cables connected to the plunger in such right angular plane to those shown for obtaining a control of the switch lever or belt shifting mechanism.

Where the mechanism operating the plunger or head block 7 is electrically controlled, in the line of circuit between the source of supply and the electric motor is positioned a switch for employing the control afforded by this invention for said mechanism. This switch consists of a fiber base 21 upon one side of which is a pair of spaced contact points 22—22 that are electrically connected to the source of supply

and the electric motor, respectively. This switch further includes a bridge contact 23 upon one end of a horizontally arranged rod 24 freely slideable through the base plate 21 and guided within bearings 25 upon the panel or supporting wall A. This rod 24 is equipped with a lateral pin 26 that projects through a vertical slot 27 in the shorter vertical arm of the bell crank 18. Obviously, when the bell crank is swung to the dotted line position in Figure 2, the bridge contact carrying rod 24 will be forced in a direction toward the right for moving said bridge contact out of engagement with the spaced contacts 22—22 resulting in the breaking of the circuit between the source of supply and said electric motor.

After the plunger or head block 7 has been properly centered within the press cylinder, the bell crank 17 will be thrown reversely to its initial position by reason of a retractile coil spring 27 anchored at its opposite end to the end of the longer arm of the bell crank and the panel or supporting wall A, respectively.

In the form of the invention disclosed in Figures 3 and 4, the invention is of such a construction as to cause the shifting of a power belt from a fixed to an idler pulley of the plunger or head block operating mechanism. In this form of the invention, the said belt is designated by the reference character 28, and in the full line position shown in Figure 4, said belt is upon the fixed pulley so that the press mechanism will be operated. On the other hand, the dotted line position of the belt is the idler position at which time said press operating mechanism is not functioning.

In carrying out my invention there is provided a belt shifting yoke 29, the end arms of which are disposed over the opposite edges of the belt, this yoke being operatively associated with a bar 30 mounted for longitudinal slideable movement within a guide bracket 31 upon the panel or supporting wall A', and being formed at its outer surface and adjacent its end opposite from that to which the yoke 29 is attached with a vertical slot 32. In this form of the invention there is pivotally attached to the panel or supporting wall A' a bell crank 33 at right angles to the yoke carrying bar 30, the short vertical arm 34 of which will engage within the slot 32 of said bar 30 to prevent its movement in either direction. The yoke 29 is normally pulled to the idling position of the belt by reason of a retractile coil spring 35, anchored at its opposite ends to the yoke 29 and the panel or supporting wall A'. Obviously, when there is an unusual pull upon either one of the cables, designated in this form of the invention by reference characters 8'—8', the bell crank lever 33 will be caused to move upwardly in the direction of

the arrow in Figure 3 for releasing the same from the bar 30. The coil spring 35 will then cause the yoke 29 to move into the dotted line position in Figure 4 for obviously sliding the belt upon the idler pulley of the operating mechanism whereby further actuation of the plunger or head block operating mechanism will be prevented.

It will thus be seen that I have provided means for automatically stopping the power mechanism of a baling press, and even though I have herein shown and described but two modifications of the invention, it is nevertheless to be understood that other forms may be provided without departing from the spirit and scope of the appended claims.

Having thus described the invention, what I claim is:

1. The combination with a baling press having a cylinder, a power operated plunger operable in said cylinder through a predetermined stroke of movement for compressing material to form a bale, said plunger being subject to canting within the cylinder during the compression stroke resulting in the formation of large ended bales, of means connected with the plunger and operable at the end of its compression stroke only when

said plunger is canted, adapted upon operation to stop the operation of the press and prevent the completion of large ended bales.

2. The combination with a baling press having a cylinder, a power operated plunger operable in said cylinder through a predetermined stroke of movement for compressing material to form a bale, said plunger being subject to canting within the cylinder during the compression stroke resulting in the formation of large ended bales, of means for controlling operation of the baling press, and means connected to the plunger for operating the last named means only when said plunger is canted at the end of the compression stroke.

3. The combination with a baling press having a cylinder, a power operated plunger operable in said cylinder through a predetermined stroke of movement for compressing material to form a bale, said plunger being subject to canting within the cylinder during the compression stroke resulting in the formation of large ended bales, of pivoted means normally retained in one position operable to stop the press, and motion transmitting means connecting the plunger with said pivoted means operable at the end of the compression stroke to move said lever for stopping the press only when said plunger is canted at the end of said stroke.

4. The combination with a baling press having a cylinder, a power operated plunger operable in said cylinder through a predetermined stroke of movement for compressing material to form a bale, said plunger be-

ing subject to canting within the cylinder during the compression stroke resulting in the formation of large ended bales, of reciprocating means directly controlling the 5 operation of the press, pivoted means normally retaining the last named means in position to permit operation of the press and plunger, and motion transmitting means con-

nected with the plunger and said pivoted means in a predetermined manner operable 10 at the end of the compression stroke for operating said pivoted means and reciprocating means to stop the press only when said plunger is canted.

In testimony whereof I affix my signature.
WALTER HANEY.
